UNITED STATES PATENT OFFICE.

FREDERICK WILLIAM STARK, OF MERIDEN, CONNECTICUT, ASSIGNOR TO INTERNATIONAL SILVER COMPANY, OF MERIDEN, CONNECTICUT, A CORPORATION OF NEW JERSEY.

DESIGN FOR A PLATE OR SIMILAR ARTICLE.

Application filed October 2, 1924. Serial No. 10,944. Term of patent 7 years.

To all whom it may concern:

Be it known that I, FREDERICK WILLIAM STARK, a citizen of the United States, residing at Meriden, in the county of New Haven, State of Connecticut, have invented a new, original, and ornamental Design for a Plate or Similar Article, of which the following is a specification, reference being had to the accompanying drawing, forming a part thereof.

Figure 1 is a plan view showing a section of the border, the complete border being made up of repeats of the parts shown; and

Fig. 2 is a side elevation of the rim, partly broken away, to show a profile of the portion carrying the ornamentation.

I claim:

The ornamental design for a plate or similar article substantially as shown.

FREDERICK WILLIAM STARK.
